UNITED STATES PATENT OFFICE.

STANLEY H. HOBSON, OF ROCKFORD, ILLINOIS, ASSIGNOR TO GEO. D. ROPER CORPORATION, OF ROCKFORD, ILLINOIS, A CORPORATION OF ILLINOIS.

END-SHELF SUPPORT.

Application filed April 16, 1925. Serial No. 23,480.

To all whom it may concern:

Be it known that I, STANLEY H. HOBSON, a citizen of the United States, residing at Rockford, in the county of Winnebago and State of Illinois, have invented certain new and useful Improvements in End-Shelf Supports, of which the following is a specification.

This invention relates to improvements in stove construction and more especially to a novel detachable stove shelf or end shelf support adapted to produce a level surface continuous with the top of the stove or to produce a neat finish with a plain square edge and surface without shoulders or locking projections, in case the end shelf is not employed by reason of lack of space or otherwise, and to simplify and improve the mounting of the end shelf and the secure retention thereof in position for use.

It has been customary in the construction of stoves and especially stove tops and shelves, to employ interlocking hooks or projections fitting in seats or openings in the top in order to detachably secure the shelf in position. This construction is objectionable because the projecting parts being of cast metal are easily breakable. Furthermore recesses are left between the shelf or top edge which leave unsightly and dirt accumulating openings. Such construction is also objectionable because it does not give a tight joint between the end shelf and the stove top or supporting edge. The present invention is designed to overcome these objections and provide a novel end shelf and supporting means therefor which facilitates the mounting of the shelf, serves to retain the shelf firmly and securely in position with a neat, tight joint conforming to the level of the top and flush against the same, as well as eliminating any openings between the two. My improved construction also provides improved means for rigidly securing the shelf in position. It further provides a neat finish in case the shelf is not employed by reason of lack of room, thus adding to the attractiveness in the appearance of the stove.

Other objects and attendant advantages will be appreciated by those skilled in this art as the invention becomes better understood by reference to the following descrip-

tion when considered in connection with the accompanying drawings, in which—

Figure 1 is a fragmentary perspective view of a stove the top of which is equipped with a detachable end shelf and supporting means constructed in accordance with the invention.

Fig. 2 is a sectional view taken on the plane of the line 2—2 of Fig. 1, and

Fig. 3 is an enlarged cross sectional view taken on the line 3—3 of Fig. 2.

Referring to the drawings in detail wherein I have illustrated an embodiment of the invention and in which similar reference characters designate corresponding parts throughout, 4 designates a stove illustrated in the present instance as a gas stove 70 having a cooking top 5 which is provided with a depending flange 6 around its edges including the side and front as indicated. This flange is provided with openings 7 therethrough preferably near the front and 75 back of the top adapted to take bolts 8 and to engage a side plate or side 9 through suitable openings 10 therein and held in position when the nuts 11 are mounted thereon and screwed into position to clamp the side. 80 The side 9 is preferably offset inwardly beneath the flange 6 as indicated at 12 so that it is brought flush with the outer face of the flange and the shoulder thus provided engages the bottom edge of the flange. 85

The shelf is indicated at 13 and has a depending marginal flange 14 to conform with the flange 6. The inner edge 15 of the shelf 13 conforms to the end of the top 5 so as to produce a tight even and level joint without 90 recesses, grooves or other crevices which otherwise render the appearance unsightly or serve to catch grease or other foreign matter. The inner side of the shelf 13 has a depending flange 16 extending downwardly at right angles the same depth as the flange 14. This flange may be cut away or recessed centrally at its bottom edge as indicated at 17 for lightness and economy in the use of material, especially where the 100 shelf is cast, and the end portions are provided with slots 18 communicating with their bottom edges. These slots permit the shelf to straddle spacing sleeves 19 mounted on the stems or shanks of the bolts 8 outwardly 105 of the flange 6, with interposed washers 20

between the sleeves and the heads of the bolts. The slots 18 are preferably slightly flared at their entrance portions at the bottom edge of the flange 16 or slotted lugs produced by the recess 17, thus permitting the sleeves to readily enter the slots 18 between the washers 20 and the face of the flange 16 so that by tightening the nuts on the bolts, the end shelf will be securely clamped and held in position. By this means, the joint between the end of the stove top and the shelf is rendered flush and level so that the surface is practically continuous and the joint entirely closed. The shelf may be readily secured in position or removed and if omitted owing to the lack of space, the sleeves 19 and washers 20 are removed from the bolts and the latter drawn tight to clamp the side 9 to the flange 6 and produce a neat finish at the end of the stove entirely free of rabbeted edges, grooves, openings, or interlocking hooks or projections which have heretofore been employed. It is also to be understood that while I have referred to the construction as particularly adapted for an end shelf, it may be used with equal facility for any other similar attachment of a shelf or other part irrespective of location.

While I have described what I now consider to be the preferred embodiment of the invention, it is to be understood that the device is susceptible of wide changes and variations in the construction, arrangement and purposes of the parts as well as the materials used, without departing from the spirit and scope of the invention as will be hereinafter defined in the claims.

I claim:

1. In a stove, the combination with a top

and an adjacent shelf to be arranged in flush, contiguous relation therewith, of a plurality of bolts passing through openings in the side of the top toward said shelf and arranged to provide projections for reception in open ended slots provided in the side of said shelf for supporting and fastening said shelf to said top in the aforesaid relation therewith and enabling tightening of the juncture between the shelf and top, said bolts being arranged to be inserted flush with the side of the top and to be tightened so as not to project from the side of the top when said shelf is not to be mounted thereon.

2. In a stove, the combination of a top having a side wall in lapping relation to a portion thereof for connection therewith, a shelf normally arranged adjacent the top in flush, contiguous relation therewith, and a plurality of supporting studs projecting from the side of the top toward said shelf for reception in open ended slots provided in the adjacent side of said shelf for supporting and fastening said shelf to said top in the aforesaid relation therewith, each of said studs comprising a bolt passing through said top and side wall arranged in lapping relation therewith, and a washer under the head thereof with a spacer sleeve therebeneath, said washer and spacer sleeve being arranged to be removed when said shelf is not to be mounted on said top whereby said bolt may be inserted with the head flush with the side of said top and tightened so as not to project from the side of the top while still serving to secure the side wall to said top as before.

STANLEY H. HOBSON.
